DESIGN FOR A TOY

Henry C. Roberts, Detroit, Mich.

Application January 26, 1946, Serial No. 126,021

Term of patent 7 years

(Cl. D34—15)

To all whom it may concern:

Be it known that I, Henry C. Roberts, a citizen of the United States, residing at Detroit, in the county of Wayne and State of Michigan, have invented a new, original, and ornamental Design for a Toy, of which the following is a specification, reference being had therein to the accompanying drawing, forming a part thereof.

In the drawing:

I claim:

The ornamental design for a toy, as shown.

HENRY C. ROBERTS.
